UNITED STATES PATENT OFFICE.

ARTHUR F. WILLIAMS, OF LOS ANGELES, CALIFORNIA.

CONTAINER.

1,294,011.

Specification of Letters Patent. Patented Feb. 11, 1919.

Application filed October 16, 1917. Serial No. 196,821.

To all whom it may concern:

Be it known that I, ARTHUR F. WILLIAMS, a citizen of the United States, residing at Los Angeles, in the county of Los Angeles and State of California, have invented new and useful Improvements in Containers, of which the following is a specification.

This invention relates to containers for confections and the like, the object being to 10 provide an inexpensive and sanitary package especially suited for paste confections, and from which the confection may be discharged by squeezing or rolling one end of the package.

15 The container comprises a paper wrapper, cut from a segmental sheet, folded into a substantially conical receptacle and a lining of the same made of grease and water-proofed paper formed of a similarly shaped 20 sheet but of larger size and folded to form double walls, the apex and base ends of the package being folded upon themselves and suitably secured together to a substantially triangular shaped package. When it is desired to discharge the contents, the apex end 25 is torn off and the base portion is squeezed to discharge the contents through the opening at the apex.

One form which my invention may assume is exemplified in the following description and illustrated in the accompanying drawings, in which—

Figure 1 shows a side elevation of a package constructed in accordance with my invention.

Fig. 2 shows a side elevation of the wrapper for the same.

Fig. 3 shows a view of the lining in partially folded position.

40 Fig. 4 shows a diagram of the sheet from which the lining is constructed.

Fig. 5 shows a diagram of the sheet from which the wrapper is constructed.

The package or container comprises, as 45 shown in its present form, a lining 10 formed of a single sheet of greased and waterproofed paper which, as shown in Fig. 4, is in the shape of a segment, one portion of which is of greater radial length than the 50 other so that an extension 11 is formed on one half thereof. This sheet is folded upon a cone-shaped die to form a receptacle of the same shape, having walls of double thickness, the shorter portion of the sheet

being on the inside. The flap 12 is disposed 55 on the outside and is suitably pasted or secured in place against the underlying sheet to hold the package closed.

A wrapper 14 is provided to inclose the lining, the wrapper being made of a single 60 sheet, as shown in Fig. 5, which is segmental in form and adapted to be folded into cone shape, with the edges overlapping and pasted or otherwise secured together. The lining is then inserted in the wrapper and 65 filled with a paste confection.

When the lining is in place within the wrapper and the package is filled with a confection, the ends are closed by folding them, as shown at 16 and 17, and suitably 70 securing them in place, preferably by means of clips 18, thereby forming a substantially triangular-shaped package. In use the apex end is torn off to expose the contents and the base portion is then squeezed or 75 rolled to force out the confection in any amount desired. If only a portion of the contents be consumed at one time, the apex end can be closed by folding, as before, and the contents will then be kept in a fresh condition indefinitely.

Such a package is inexpensive and easy to make, has moisture and vermin-proof qualities, and while primarily intended for confections, being a convenient and cleanly 35 method of dispensing sticky substances of this nature, it may also be used for packaging other kinds of material.

Having thus described my invention, what I claim and desire to secure by Letters Patent is—

1. A wrapper comprising a single sheet of material composed of two segmental fields of unequal radial length and having a common center whereby a cone may be formed 95 from said sheet having a continuous inner and outer wall and provided with a sealing flap at its base.

2. A package or container comprising a segmental sheet of material adapted to be 100 wrapped to form a cone having a continuous two-ply wall and means whereby the outer ply will form a sealing flap for the base of the container.

3. A container comprising a sheet of material representing segments of a circle emanating from a common center and described by radii of form lengths, said material being

rolled upon itself to dispose the segmental portion of the sheet of shorter radial length within the portion of the sheet of longer radial length, whereby a container will be formed having a two-ply wheel and a one-ply mouth portion which may be folded to provide a closure for the container.

In testimony whereof I have hereunto set my hand in the presence of two subscribing witnesses.

ARTHUR F. WILLIAMS.
